UNITED STATES PATENT OFFICE.

WILLIAM A. COVENTRY, OF LANCASTER, PENNSYLVANIA, ASSIGNOR TO GREY IRON CASTING COMPANY, OF MOUNT JOY, PENNSYLVANIA, A CORPORATION OF PENNSYLVANIA.

WHEELED TOY.

1,236,149.

Specification of Letters Patent.

Patented Aug. 7, 1917.

Application filed March 28, 1917. Serial No. 157,920.

To all whom it may concern:

Be it known that I, WILLIAM A. COVENTRY, a citizen of the United States, and a resident of the city of Lancaster, in the 5 county of Lancaster, State of Pennsylvania, have invented certain new and useful Improvements in Wheeled Toys, of which the following is a specification.

This invention relates broadly to toys and 10 more particularly to a toy car of novel construction.

The principal object of the present invention is to produce a toy comprising a representation of a railway car and so constructed 15 as to be cheap to manufacture and economical to assemble.

A further object of the present invention is to provide a toy car of the character specified with automatic coupling devices where- 20 by a plurality of such cars may be coupled together as a train.

A still further object of the present invention includes a novel roof structure for toy cars and the like.

25 Other and further objects of the present invention will in part be obvious and will in part be pointed out hereinafter in the specification following by reference to the accompanying drawings wherein like parts are 30 represented by like characters throughout the several figures of the drawings.

Figure 1 is a view showing an elevation of a car constructed in accordance with the present invention.

35 Fig. 2 is a plan view of the device disclosed in Fig. 1.

Fig. 3 is a section taken on section line 3—3 of Fig. 1.

Fig. 4 is a detail view of the preferred 40 form of roof construction.

Fig. 5 is a detail view of a modified form of roof construction.

Fig. 6 is a view showing the operation of the coupling device as illustrated by an ele- 45 vational view.

Fig. 7 is a detail sectional view taken on line 7—7 of Fig. 6.

Fig. 8 is a detail view showing a section taken on substantially line 8—8 of Fig. 7.

50 Heretofore in the art the most common manner of assembling toy cars and the like has been to provide suitable car bodies formed in sections and adapted to be secured together by rivets so that the sections

formed the complete car body including the 55 roof. In this type of construction any slight variation between the portions forming the roof left an unsightly opening on the center line of the car in the middle portion of the roof which is the most prominent portion 60 of the toy when it is on the floor where such toys are usually placed. Also in the art of toy cars it has been common to provide depending portions through which truck axles, 65 usually comprising pieces of wire, were adapted to extend with the wheels on the outside of the truck frames. This construction necessitates the threading of the axles through the bearings and the riveting of the 70 wheels on the axles so that the wheels are on the outside of the truck frames. Also this construction necessitates more or less skilled labor in assembly of the parts. Still further the prior art shows various types of couplers 75 particularly wire devices for forming the individual cars into trains. Such devices are not ordinarily automatic in their operation, and furthermore, the introduction of wire devices brings in an added expense in both assembly and production.

80 The present invention comprises more particularly the production of a toy car obviating the foregoing difficulties as specified inherent in the known prior art and also to provide a novel construction. A toy car in 85 accordance with the present invention comprises a representation of a car wherein the body portion of the car is formed by mating a pair of similar side castings. Each side casting is identical in shape and form 90 and all of the side castings might be made from a single mold. They are so constructed that when mated interlocking portions fit properly to position and aline the side members. These side members are suitably 95 spaced by vestibule partitions and vestibule floors which extend inwardly to the middle of the assembled car. The roof comprises a continuous sheet of metal shaped to conform to the outline of a car roof and adapted to be secured to the portion of the sides of the car representing the sides of the upper deck of a passenger car. The truck frames are cast integral with the sides of the cars and each pair of wheels is cast integral with the axle which terminates in stub axles extending from each wheel. These stub axles extend through the bearings in the truck

frames so that when the stub axles are properly positioned and the sides fitted together the trucks are automatically assembled without riveting. The side frames, so far as the 5 floor is concerned, are open, except for the vestibule platform, and where desired a sheet of metal may be positioned within the side frames to constitute a suitable car floor. The sides of the car may be suitably secured 10 together by a single rivet placed substantially midway of the sides and extending from side to side of the car.

An automatic coupler is provided and comprises a cast iron latch in substantially 15 U-shaped form with the latch portion above the vestibule car floor and a weighted portion below the vestibule car floor with a flat connecting portion extending through an opening one-half of which is provided in 20 each section of the vestibule car floor. The latch portion of the coupler is adapted to latch into and engage a similar opening in the end of an adjacent car, whereby in order to enable the cars to be formed into trains 25 each car carries a latch member at one end and is provided with a coupler opening at the other end. This construction provides a neat, cheap and satisfactory toy car.

Referring now more particularly to the 30 drawings, the side sections 1 are provided with vestibule floors 2 wherein one-half of the vestibule floor is carried by each side section, and the side section at one end is provided with a projection 4 and at the 35 opposite end is formed with a companion depression 5 whereby when two side sections are paired together the projection and depression interlock as illustrated in Fig. 7. Each section 1 is also provided with a floor sill 6 40 which extends longitudinally of the section from the vestibule floor at one end to the vestibule floor at the opposite end. The vestibules at each end are likewise provided with vertical partitions 7, one-half of such 45 partitions being carried by each side section and these partitions are likewise provided with projecting tongues 8 and corresponding receptacles 9 whereby these members 8 and 9 also interlock when the side sections are 50 suitably paired as illustrated in Figs. 4 and 5. The side members 1 carry suitable truck frames 10 which may be provided with a plurality of bearings 11 comprising merely 55 openings through the truck frames. Pairs of wheels 12 are preferably cast integral with an axle 14 and provided with stub axles 15 that extend outwardly from the wheels 12 and through the bearings 11. The side sections 1 may be secured together by means 60 of a through rivet 16 which when suitably positioned firmly locks the two side sections together. The roof preferably is formed of sheet metal 17 shaped to simulate a car roof and may be provided with links 18 that 65 are adapted to be extended through the

ventilating openings 19 in the side members 20 of the upper deck of the car. If desired the roof sheet may be positioned by bending the edges to constitute flanges 21 which extend under these side members 20 as shown 70 in Fig. 5.

The coupler mechanism comprises a suitable cast metal latch of substantially U-shaped form wherein the latch arm 22 carrying the latch head 24 is mounted above 75 the vestibule car floor and the weight 25 is beneath the vestibule car floor with a flat connecting portion 26 integrally securing the latch arm to the weight. Preferably the metal adjacent the pivot of the latch is 80 rounded, as at 27 and 28, to facilitate the action of the coupler. Openings 29, one-half of which is provided in each vestibule car floor, comprise either a suitable mount for the coupler latch or a suitable opening into 85 which the coupler head may interlock to couple individual cars into trains (see Figs. 6 and 7). The rounded end 30 on the latch head and the coupler weight 25 cause the coupler latch to be automatic in its operation so that when two cars are suitably moved with their vestibules adjacent to cause one car to approach the other the coupler latch automatically secures the cars 90 together thereby simulating the function of the automatic couplers used in real train service.

Realizing that my invention may be embodied in structures other than those specifically disclosed herein I desire that the disclosure herewith be considered as illustrative and not in the limiting sense.

Having thus described my invention what I claim is:

1. A toy car comprising side members 105 formed of identically the same shape and each side comprising substantially one-half of a car body, each side member having horizontal vestibule floor portions extending substantially to the middle of the car at the 110 ends of the car, vertical vestibule portions at the ends of the car and extending to the middle of the car adjacent the upper portion of the car, floor supports extending along the lower inner sides of the car, a 115 sheet metal floor adapted to be supported upon the said floor supports, and means comprising a sheet metal roof to lock the sides of the car together.

2. A toy car formed of side members of 120 identically the same shape and each side member comprising substantially one-half of the car body, truck frames integral with the said sides and extending beneath the said sides and provided with bearing openings, 125 truck members comprising wheels with an axle between the wheels and stub axles extending outside of the wheels and adapted to extend into and be supported within the said bearings, and means for locking the 130

sides together to form a complete car and retain said trucks within said truck frames.

3. As an article of manufacture, a toy car comprising in combination, a pair of sides 5 formed of identically the same shape and adapted when reversed to be complementary one to the other, vestibule floors formed integral with said side members and extending to the middle of said car, vestibule partitions adjacent the ends of the car and having portions extending to the middle of the car, a sheet metal roof over the upper portion of said sections and adapted to lock the upper portion of said sections together, and 10 rivet means for locking the sides of said car together.

4. In a toy car of the character described, a coupling mechanism comprising a toy car structure provided with an opening in the 15 end platform thereof, a coupler latch pivotally mounted within said opening, said coupler latch having an arm provided with a latch head on the end of said arm, a downwardly extending member integral with the 20 other end of said arm, and a weight integral with said downwardly extending member, said weight being positioned toward said latch head whereby gravity acting on said weight and latch head returns said 25 latch head to horizontal position when same is released after being displaced upwardly to enable said latch head to engage an open-

ing in an adjacent car to couple the cars together.

5. In a toy car of the character described, 35 an automatic coupling mechanism comprising a coupler having an arm extending above the end platform of a car, a latch head on the end of said arm and positioned outwardly beyond the end of said platform, 40 the advancing face of said latch head being downwardly inclined, a weighted arm extending beneath said first mentioned arm, and means connecting said weighted arm and the first mentioned arm to permit the 45 latch head to be raised and dropped into an opening in an adjacent car to couple the cars together.

6. In a toy car of the character described, 50 an automatic coupler comprising an arm normally resting on the end platform in substantially a horizontal position, a coupler latch head on the outer end of said arm and extending outwardly from said platform, the advancing face of said coupler 55 head being suitably inclined to permit said coupler head to engage and be retained within a suitable interlocking recess in an adjacent car, and means for enabling said arm to pivot relatively to said car platform to permit said coupler head to interlock as specified. 60

WILLIAM A. COVENTRY.
